UNITED STATES PATENT OFFICE.

ALBERT SHUTT, OF TOPEKA, KANSAS.

DESIGN FOR A BODY FOR STRINGED MUSICAL INSTRUMENTS.

41,792.

Specification for Design.

Patented Sept. 19, 1911.

Application filed May 22, 1911. Serial No. 628,871. Term of patent 14 years.

To all whom it may concern:

Be it known that I, ALBERT SHUTT, a citizen of the United States, residing at Topeka, in the county of Shawnee and State of Kansas, have invented a new, original, and ornamental Design for Bodies for Stringed Musical Instruments, of which the following is a specification, reference being had to the accompanying drawing, forming part thereof.

Figure 1 shows the design of the body of a stringed musical instrument in front elevation; Fig. 2 is an edge view thereof.

I claim:

The ornamental design for a body for stringed musical instruments as shown.

ALBERT SHUTT.

Witnesses:

FRANK J. OPPITZ,
VICTOR W. RAUSCH.
